CLAIM

The ornamental design for a camera, as shown and described.

DESCRIPTION

FIG. 1 is a front view of a camera showing our new design. FIG. 2 is a rear view of our new design shown in FIG. 1. FIG. 3 is a left-side view of our new design shown in FIG. 1.

FIG. 4 is a right-side view of our new design shown in FIG. 1.

FIG. 5 is a top view of our new design shown in FIG. 1. FIG. 6 is a bottom view of our new design shown in FIG. 1. FIG. 7 is a perspective view of our new design shown in FIG. 1.

The broken lines in the drawings illustrate portions of the camera and form no part of the claimed design.

1 Claim, 3 Drawing Sheets
